(57) **CLAIM**

The ornamental design for a range hood main body as shown and described.

DESCRIPTION

FIG. 1 is a front, top, right perspective view of a range hood main body, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom, left perspective view thereof.

The dashed broken lines in the drawing depict portions of the main body of the range hood that form no part of the claimed design.
